Robinson IP Law, PLLC

(57) **CLAIM**

The ornamental design for a collapsible pet carrier, as shown and described.

DESCRIPTION

FIG. 1 is a front right perspective view of a collapsible pet carrier showing my new design;

FIG. 2 is a front view of the collapsible pet carrier of FIG. 1;

FIG. 3 is a back view of the collapsible pet carrier of FIG. 1;

FIG. 4 is a top view of the collapsible pet carrier of FIG. 1;

FIG. 5 is a bottom view of the collapsible pet carrier of FIG. 1;

FIG. 6 is a right view of the collapsible pet carrier of FIG. 1;

FIG. 7 is a left view of the collapsible pet carrier of FIG. 1.

FIG. 8 is a bottom back perspective view of the collapsible pet carrier of FIG. 1 in a partially collapsed position; and,

FIG. 9 is a top right perspective view of the collapsible pet carrier of FIG. 1 in a completely collapsed position.

Shading is provided to show contour and not surface ornamentation. The broken lines portions are for illustrative purposes only and form no part of the claimed design.

1 Claim, 9 Drawing Sheets
